UNITED STATES PATENT OFFICE.

JOHN W. MACDONALD, OF PITTSBURG, PENNSYLVANIA.

BLAST-FURNACE.

No. 860,983.

Specification of Letters Patent.

Patented July 23, 1907.

Application filed June 12, 1905. Serial No. 264,789.

To all whom it may concern:

Be it known that I, JOHN W. MACDONALD, a citizen of the United States, residing at Pittsburg, in the county of Allegheny and State of Pennsylvania, have 5 invented an improvement in that class of blast-furnaces in which the walls thereof next the points of greatest heat are formed of a series of water-cooled metal jackets, which consists in arranging the twyers for such furnaces in specially-constructed water-cooled chambers 10 independent of said metal jackets and designed to be separately removable from the furnace-walls without disturbing any part of said walls.

It is well understood by those familiar with the present method of arranging the twyers in, and the operation 15 of furnaces of the class referred to, that owing to the expansion and contraction of the metal forming the inside sheets of the water jackets of such furnaces, said sheets frequently become warped and buckle up, and that this warping and buckling causes the joints 20 formed between the twyers and said jackets to open up and permit the water in said jackets to leak out into the furnace, preventing its successful operation, and often making necessary the removal of one or more of 25 said jackets, which cannot always be done without closing down the furnace. In either event the output of the furnace is reduced with consequent loss.

The object therefore of this improvement is to avoid the annoyances and loss arising from the present practice of making the twyers form part of the water jackets 30 of furnaces of the class referred to.

The specification here following, taken in connection with the drawings attached, form a description of said improvement.

Figure 1 is a vertical cross section of one wall of a 35 furnace of the class referred to, showing water jacket and the application of this improvement. Fig. 2 is a perspective view of one of the twyer chambers removed, and Fig. 3 is a sectional view of said twyer chamber on a line drawn through the twyers.

40 In applying said improvement, a series of twyer chambers are cast from some suitable metal, preferably in the form shown, having an outer casing 2, of such size as to contain one or more twyers 3 and provide the water space 4, and having openings 5 and 6 45 to receive water supply and discharge pipes 7 and 8. As these twyer chambers are designed to form a section of the furnace walls, on the line of the furnace twyers, that part of said walls with which this improvement has to do, is divided into a lower section 9 and an upper 50 section 10, between which sections said twyer cham-

bers are arranged as shown in Fig. 1. Section 9 of said walls extends from the furnace hearth up to said twyer chambers, and is formed of a series of short water jackets; or it may be built up of suitable brick, and section 10 extends from said twyer chambers to a height 55 common to such form of furnace, and is constructed of water jackets of the usual form, suspended from the substructure of the furnace in the manner commonly practiced, leaving sufficient space between said sections to receive said twyer chambers. Said twyer chambers 60 may be made any desired length, but it will be understood that as said chambers are to occupy the whole space between the upper and lower sections of the furnace walls, the length and number thereof must be such that when placed in position, with their ends 65 joining, said chambers will neatly close the gap between said sections. Said chambers are held in place by means of clamps 11, and water is circulated through them by means of pipes 7 and 8, which connect with main pipes for the supply and discharge of water to 70 and from other parts of the furnace. Pipe 12 for the supply of blast connects with each of the twyers 2 in the ordinary way. By disconnecting pipes for the supply of blast, and pipes 7 and 8, and releasing clamps 11, any one or more of said twyer chambers may be re- 75 moved as desired. It will be seen that if said twyer chambers are casted from suitable metal, with all corners made rounding, danger of their cracking and causing leaks will be reduced to a minimum, and as the twyers are removed from the water jackets, the existing 80 cause of leaks at the twyers under present practice is eliminated in the construction here shown.

What I claim and desire to secure by Letters Patent, is

1. In a furnace of the class described, having the walls 85 thereof, formed of water jackets, a series of small outwardly removable water cooled chambers containing the furnace twyers, contiguously arranged in the furnace walls in such manner as to form when in place, a section of said walls, and clamps for holding said chambers in position; as shown and described, and for the purpose set forth.

2. In a furnace of the class described, having the walls 90 thereof formed of water jackets, twyers forming an integral part of outwardly removable water cooled chambers 95 contiguously arranged in the furnace walls in such manner as to form, when in place, a section of said walls, and clamps for holding said chambers in position; as shown and described, and for the purpose set forth.

3. In a furnace of the class described, having the walls 100 thereof arranged in upper and lower sections, twyers forming an integral part of water cooled chambers contiguously arranged in said walls intermediate of the upper section and lower section thereof; the said chambers form-

ing, when in place, a section of said walls, and being outwardly removable therefrom, and clamps for holding said chambers in position; as shown and described and for the purpose set forth.

5 4. A furnace of the class described, having the walls thereof formed of water jackets arranged in upper and lower sections, a series of small outwardly removable water cooled chambers containing the furnace twyers, contiguously arranged in the furnace walls, intermediate of

said upper and lower sections of water jackets, in such 10 manner as to form when in place, a section of the furnace walls, and clamps for holding said twyer chambers in position; as shown and described and for the purpose set forth.

JOHN W. MACDONALD.
